UNITED STATES PATENT OFFICE.

CHARLES VAN CISE WHEELER, OF ALLEGHENY, AND ALEXANDER GEORGE MCKENNA, OF BRADDOCK, PENNSYLVANIA, ASSIGNEES TO FIRTH STERLING STEEL COMPANY, A CORPORATION OF PENNSYLVANIA.

CAP FOR PROJECTILES.

SPECIFICATION forming part of Letters Patent No. 748,827, dated January 5, 1904.

Application filed May 1, 1903. Serial No. 155,092. (No model.)

To all whom it may concern:

Be it known that we, CHARLES VAN CISE WHEELER, of Allegheny, and ALEXANDER GEORGE MCKENNA, of Braddock, in the State of Pennsylvania, citizens of the United States, have invented certain new and useful Improvements in Caps for Projectiles, of which the following is a specification, accompanied by drawings.

This invention relates to caps for projectiles, and has for its objects to improve upon the effectiveness of the cap with which modern armor-piercing projectiles are provided and also to decrease the liability of accident 5 through the cap becoming detached in the gun, and so jamming the projectile therein.

Further objects of the invention will hereinafter appear; and to these ends the invention consists of a projectile provided with a cap for carrying out the above objects embodying the features of construction, combinations of elements, and arrangement of parts, substantially as hereinafter fully described and claimed in this specification and 25 shown in the accompanying drawings, in which—

Figure 1 is a longitudinal sectional view through an armor-piercing projectile provided with a cap constructed in accordance 30 with this invention. Fig. 2 is a transverse sectional view on the line XX of Fig. 1, showing the method of inserting the fastening devices for the cap. Fig. 3 is a transverse sectional view on the line XX of Fig. 1 after the 35 fastening devices have been raised in place. Fig. 4 is an enlarged detail view, in longitudinal section, through the projectile, showing the manner of forcing a tight fit between the projectile-point and the cap.

Various means and devices have been invented for attaching the cap to the head of the projectile—as, for instance, by means of movable set-screws, unhooking-clamps, or by unlocking slot devices, and by forming an annular rib on the insice of the cap adapted to be compressed into a groove on the head of the projectile. Caps have been also secured to the projectile by means of soft solder or by means of a retaining rib or ribs provided 45 upon the projectile-point. In those instances 50 in which the cap is made detachable by means

of removable set-screws and the like the fastenings are likely to become loose, and this is a vital objection. Where it becomes necessary to compress metal into a groove on 55 the head of the projectile, the metal of the cap must be soft enough to be forced cold into the groove without rupture, and thus according to this construction advantage cannot be taken of material possessing great 60 crushing strength which can deliver a more effective blow in cracking the hard face of the latest type of armor-plate than soft material. It is extremely difficult, even with soft material, to completely fill the groove in 65 the head of the projectile, notwithstanding the use of hydraulic pressure, for the material of the cap cannot be prevented from flowing longitudinally instead of laterally, thereby rendering the attaching means imperfect, but with the imperfection so concealed 70 that they are not to be discovered by subsequent inspection. The head of the projectile has also been provided with a groove, and a rib on the cap has then been shrunk into the 75 groove to hold the cap in position; but this construction may lead to heating the point of the projectile, and thus softening it perceptibly, which is a very detrimental desideratum against present armor-plates. The 80 use of solder also involves heating and softening of the projectile-point and a thoroughly-reliable fastening is not obtained. The provision of ribs on the projectile-point is objectionable not only because of the difficulty of machining such shapes, but also in 85 requiring increased energy for such contour of point to perforate the plate.

According to our construction both the cap and the head of the projectile are provided 90 with grooves which are adapted to substantially register when the cap is in position on the point of the projectile and means are provided for inserting a fastening device or devices within the grooves in the cap and projectile.

Referring to the drawings, A represents a projectile, and B the cap therefor. The cap is provided with a groove C on the inside of the same, which groove is adapted to register with the groove D on the head of the projectile when the cap is placed in position. As

- shown in this instance, these grooves are annular in form and lie in a plane substantially perpendicular to the axis of the projectile, although it is obvious that other arrangements of grooves may be provided, and while the grooves together form an annular recess of circular cross-sectional outline it is to be observed that the grooves may be constructed of other shapes.
10. Means are provided for inserting suitable fastening devices in the form of pins or rods E within the annular keyway formed by the grooves C and D. These devices E form keys for holding the cap in position upon the projectile-point. In this instance the grooves in the cap are shown communicating with the exterior of the cap for the insertion of the fastening devices E. These rods are forced into the grooves by any suitable means—as, for instance, by blows delivered by a hammer.
- As shown in Fig. 4, the grooves C and D nearly coincide or in exactly register, and it will be seen that when the rods or fastening devices E are driven home the cap will be drawn tightly down over the point. The cap being placed in position and held tightly therein by suitable means, the rods E, which may have rounded points and may be made of steel, are forced into the groove. The rods are shown of sufficient length to completely fill the grooves and are shown inserted through the latitudinal holes in the opposite sides of the cap. It is evident that the cap so secured in position can only be displaced by shearing the entire rod longitudinally or by forcing the cap metal to flow to a very considerable amount. In practical operation the insertion of the steel rods E is found to be very simple, while a very great force is required to displace the cap. A very small groove can be used, if desired, thus diminishing the risk of weakening the projectile-point. This would be more important on large-caliber projectiles.
45. If desired, the rods E may be of slightly larger diameter than the grooves, thus insuring the tightest and most secure fastening possible. The fastening rods need not be circular in cross-section, but may be of any equivalent construction suitable for the purpose desired, and it will be seen that the insertion of the rods applies a wedging force which is extremely powerful.
- According to this invention all of the objections to former caps are removed, for the cap may be made of material of any required crushing strength, and a cap so fastened can only be removed by the application of sufficient power to distort the entire base of the cap. Each cap is furthermore necessarily fastened in exactly the same efficient and uniform manner. The operation of the fastening cannot be done clumsily without instant detection.
65. As no heat is applied to the point of the projectile, it is not softened. In oblique impacts it is particularly important that the

cap shall be securely fastened, so that as the edge of the cap impinges on the plate the projectile may to a certain extent pivot on it and enter the plate on a line normal to the surface, thus avoiding glancing effects due to the cap becoming detached at the moment of impact, and our invention carries out all the required objects.

Obviously this invention may be embodied in varying forms, and some features of the invention may be used without others.

Therefore, without limiting the invention to the construction shown and described nor enumerating equivalents, we claim, and desire to obtain by Letters Patent, the following:

1. A projectile and a cap therefor, both having grooves, and means coöperating with said grooves for holding the cap in position on the head of the projectile, for substantially the purposes set forth.

2. A projectile and a cap therefor, both having grooves, and means coöperating with said grooves for holding the cap in position on the head of the projectile, the cap having provision for the insertion of said holding means from the outside, for substantially the purposes set forth.

3. A projectile and a cap therefor, both having grooves, and means coöperating with said grooves and adapted to assume a curved shape conforming to the periphery of the projectile for holding the cap in position on the head of the projectile, the cap having provision for the insertion of said holding means from the outside, for substantially the purposes set forth.

4. A projectile, having a groove in its head portion, and an interiorly-grooved cap adapted to fit over the head, the groove in the cap substantially registering with the groove in the head, and fastening means lying within the groove on the head and cap, for substantially the purposes set forth.

5. A projectile, having a groove in its head portion, and a cap provided with an interior groove opening to the exterior of the cap and adapted to register with the groove on the head when the cap is in position on the point of the projectile, and a rod or key lying within both of said grooves, for substantially the purposes set forth.

6. The combination of a projectile and a cap therefor, both provided with grooves adapted to register when the cap is in position on the head of the projectile, a rod or rods, and means for inserting said rod or rods in the registering grooves from the outside, for substantially the purposes set forth.

In testimony whereof we have signed this specification in the presence of two subscribing witnesses.

CHARLES VAN CISE WHEELER.
ALEXANDER GEORGE MCKENNA.
